UNITED STATES PATENT OFFICE.

PHILIP LINDEMAYER, OF BALTIMORE, MARYLAND, ASSIGNOR TO THE AMERICAN STOPPER COMPANY, OF NEW YORK, N. Y.

BOTTLE-CLOSING CAP.

SPECIFICATION forming part of Letters Patent No. 651,369, dated June 12, 1900.

Application filed October 5, 1899. Serial No. 732,741. (No model.)

To all whom it may concern:

Be it known that I, PHILIP LINDEMAYER, a resident of the city of Baltimore, in the State of Maryland, have invented certain new and useful Improvements in Bottle-Closing Caps; and I do hereby declare the following to be a full, clear, and exact description of the invention, such as will enable others skilled in the art to which it pertains to make and use the same.

The invention relates to caps for closing bottles and the like, and has for its object to provide for the more uniform distribution of metal by crimping the cap-flanges uniformly throughout their whole extent, said flanges having lugs formed in the crimped portions.

The invention consists in the construction hereinafter described and pointed out.

In the accompanying drawings, Figure 1 is a side elevation of the improved cap. Fig. 2 is a perspective. Fig. 3 is a central longitudinal section. Fig. 4 is a section on line 4 4 of Fig. 1.

Numeral 1 denotes a cap-flange provided with crimps or corrugations throughout its whole extent.

2 denotes a shoulder formed in the cap which, among other functions, adds to the rigidity of the cap and tends to avoid spreading of the same.

3 denotes indentations in the cap above the shoulder. In some cases these may be omitted, and also the shoulder, if desired.

4 denotes lugs formed in the crimped flange and preferably retaining the crimps. They are produced by slitting the flange before or after crimping the cap and indenting a portion of the metal adjacent the slit. The sharp metal edge of a lug thus formed is held to the corresponding lug or incline of

the bottle without slipping, and very securely, and such a lug can yield when necessary to permit screwing on of the cap.

The crimps in the cap-lug provide that they can be indented with less drawing of the metal and with less danger of fracture. If the crimps in the lug in its initial state are not entirely removed by indenting the same, but remain in the lugs, the latter have a greater extent in a radial direction and have, therefore, a greater extent of bearing edge.

I am aware that longitudinally-crimped caps have been provided with plain faces intermediate the crimps, said faces having inwardly-projecting lugs, and such construction is not of the present invention, which is characterized by lugs formed transversely of the crimps in caps having no plain faces intermediate said crimps. Such plain faces have heretofore been regarded as necessary, but I have found that lugs can be formed in the crimped portion, and said lugs have greater strength and a better bearing-surface.

Having thus described my invention, what I claim is—

1. A cap for closing bottles and the like having its flange longitudinally crimped and having lugs formed in the crimps.

2. A cap for closing bottles and the like having its flange longitudinally crimped and lugs formed in the crimps, said lugs being formed by slitting the metal circumferentially and indenting it adjacent the slits.

In testimony whereof I have signed this specification in the presence of two subscribing witnesses.

PHILIP LINDEMAYER.
